UNITED STATES PATENT OFFICE

ERNEST DICKEY, OF DAYTON, OHIO, ASSIGNOR TO DELCO-LIGHT COMPANY, OF DAYTON, OHIO, A CORPORATION OF DELAWARE

ELECTRICAL APPARATUS

Application filed February 23, 1926. Serial No. 89,995.

The present invention relates to internal combustion engines and more particularly to the control of the ignition circuit and the throttle valve of the engine.

5 When engines are utilized for certain purposes, it is desirable to control the throttle valve of the engine in response to the speed thereof; also it is desirable that the ignition circuit be interrupted when the engine is 10 idle.

An economical manner of manufacturing such control is to provide one engine operated device for controlling both the throttle valve and the ignition circuit. In that type 15 of control there are certain disadvantages, for example, the attendant, while intending to complete the ignition circuit, may move the control to such a position as to materially affect the adjustment of the throttle valve so 20 as to render engine starting difficult, or, while attempting to adjust the throttle, the attendant may interrupt the ignition circuit.

One of the objects of the present invention is to simplify the starting operation of the 25 above type of ignition and throttle valve control. One manner of carrying out this object is to provide an auxiliary ignition control which is segregated, to a certain extent, from the common valve and ignition control and 30 which is operable for engine starting purposes and which may be rendered inoperative after the engine speed control is effective for maintaining the ignition circuit.

Further objects and advantages of the 35 present invention will be apparent from the following description, reference being had to the accompanying drawings, wherein a preferred form of the present invention is clearly shown.

40 In the drawings:

Fig. 1 is a fragmentary front view of an internal combustion engine showing the present invention applied thereto.

Fig. 2 is a sectional view of certain of the 45 control elements utilized in the present invention, the view being taken looking in the direction of the arrow 2 of Fig. 1.

Fig. 3 is a sectional view taken on the line 3—3 of Fig. 2.

50 Referring to the drawings, 20 indicates an

internal combustion engine having a fuel intake 21 connected with a carburetor 22. A fuel mixture passage 23 of the carburetor 22 is controlled by throttle valve 24. Throttle valve 24 is secured to a shaft 25, which extends through a wall of the carburetor. This extending portion of the shaft carries a lever 26 having a weighted arm 27 and an arm 28. Arm 28 carries a pin 29 which is arranged to slide within a slot 30 of a lever 31 thus forming a non-articulated connection between the arm 28 and lever 31.

An operating shaft of the engine, such as a timer or cam shaft, drives a centrifugally operated device 33 enclosed within a housing 34. The device 33 includes fly-balls 35 arranged to move a plunger 36 inwardly when said weights are moved outwardly by centrifugal force. Lever 31 is pivoted at 38 on the housing 34 and an arm 39 of lever 31 is arranged to engage the plunger 36. The weight 27 of lever 26 normally tends to rotate the arm 28 counterclockwise, which in turn tends to rotate lever 31 clockwise. Therefore, the arm 39 will always be maintained in engagement with the plunger 36. When the engine is in operation, the fly-balls will move outwardly and the plunger 36 will be moved inwardly, thus permitting the weight 27 to move downwardly whereby to control the throttle valve 24.

A supporting plate 41 is suitably secured to the housing 34 and carries switch mechanism including a terminal plate 42 of insulating material. Plate 42 carries terminal or contact 43 and terminal 44, which terminals are connected respectively with wires 45 and 46. Terminal 44 carries springs 48 and 49, the ends of which provide contacts 48a and 49a respectively. Spring 48 normally tends to move contact 48a out of engagement with contact 43 while spring 49 normally tends to move contact 49a into engagement with contact 43. A cover 50 for the aforementioned switch mechanism has its top portion 51 perforated as at 52 above the spring 48. A button 54 extends through the opening 52 and engages spring 48 by which the contact 48a can be moved into engagement with contact 43. Contact 49 carries a plate 55 of insu-

lating material which lies in the path of movement of an arm 56 carried by the lever 31.

Fig. 2 shows the switch mechanism in detail with the arm 56 of lever 31 operatively associated therewith. The normal positional relation of the elements is indicated in Fig. 1 but for convenience of illustration the switch mechanism has been placed to the left of the lever 31 in Fig. 2. It is of course obvious if the exigencies of engine design necessitate the particular positioning shown in Fig. 2 that the bottom surface of arm 56 may be suitably beveled in order to impart sufficient movement to the contact arm 49.

Ignition for the engine is furnished by an ignition device 60 the primary winding of which is connected with wire 45 and the secondary winding is connected to a spark plug 61 by a wire 62.

When the engine is at rest the lever 31 is in such position that the arm 56 engages plate 55 to maintain the contact 49a out of engagement with the contact 43. In order to supply ignition to the engine for starting purposes the button 54 is forced downwardly causing spring 48 to engage the horizontal portion of contact member 43, thus completing the ignition circuit through the primary. After the engine becomes self-operative and the speed thereof increases to a predetermined amount the fly-balls 35 will be moved outwardly sufficiently whereby lever 31 will be moved to such position that the arm 56 will be out of engagement with the plate 55 and the spring 49 will then force contact 49a against contact 48a. In this manner the ignition circuit will be made between contact 43 and terminal 44 through the contacts 49a and 48a. The button 54 can then be released whereby the contact 48a will move out of engagement with the contact 43. Ignition will then be maintained solely through the contact 49a. When the speed of the engine falls below a predetermined value, arm 56 will engage plate 55 to separate contact 49a from contact 43 thus interrupting the ignition circuit.

By utilizing the present invention the control of the internal combustion engine has been simplified. One engine speed control device is used for controlling the ignition circuit and the throttle valve of the engine and the construction and arrangement of the switch mechanism is such that ignition may be furnished to the engine, as for example, during the starting operation, without affecting the position of the throttle valve. Thus it is not necessary to disturb the throttle valve in order to complete the ignition circuit during the starting operation, and the necessity of manually holding the throttle valve in a certain position, suitable for providing the correct amount of fuel, and, at

the same time provide ignition for the engine, has been removed.

The arrangement hereinbefore described and illustrated is very compact and readily accessible and the absence of articulated connections between the various levers permits considerable flexibility in the testing of the air and electric systems during operation of the engine.

While the form of embodiment of the invention as herein disclosed, constitutes a preferred form, it is to be understood that other forms might be adopted, all coming within the scope of the claims which follow.

What is claimed is as follows:

1. In combination, a prime mover, a movable throttle for the prime mover, ignition means for the prime mover, a circuit for said ignition means, and a prime mover speed responsive device for controlling the movement of the throttle and for rendering the ignition circuit inoperative when the speed of the prime mover has reached a predetermined low value.

2. In combination, a prime mover, a movable throttle for the prime mover, ignition means for the prime mover, a circuit for said ignition means, a governor responsive to the speed of the prime mover, and means actuated by said governor for controlling the throttle and for rendering the ignition circuit inoperative when the speed of the prime mover has reached a predetermined low value.

In testimony whereof I hereunto affix my signature.

ERNEST DICKEY.
